UNITED STATES PATENT OFFICE.

CHARLES E. McDONNELL, OF QUINCY, ILLINOIS.

FUEL-FEEDING APPARATUS.

Application filed July 21, 1926. Serial No. 124,082.

This invention relates to improvements in devices particularly designed for charging coal gas retorts. It is not, however, limited to this particular use as it is well adapted for handling other materials such as sand, gravel and the like.

In the charging of coal gas retorts it is necessary that the coal be projected a minimum distance of twelve feet and the maximum distance is approximately twenty-three feet and an object of the present invention is to provide a coal charging mechanism capable of delivering the coal these distances, depending upon the size of the retort.

The result sought is best accomplished with sectional impellers in order to prevent clogging of the mechanism. These impellers are preferably pivotally carried on a rotatable shaft, and a further object of the invention is to provide means for supporting these sectional impellers on the shaft in such wise that their pivot members will be reinforced against any bending stresses imposed upon the same when the impellers encounter the material being handled.

With these and other objects in view the invention consists in certain novel details of construction and combinations and arrangements of parts all as will hereinafter be more fully described and the novel features thereof particularly pointed out in the appended claims.

In the accompanying drawings,—

Figure 1 is a side elevation with the casing partly broken away to show the interior parts of the device; and

Fig. 2 is an edge view looking into the discharge opening, the upper portion of the casing being broken away.

Fig. 3 is a diagrammatic illustration of the assembly of the impellers.

The fuel feeding device comprises a casing 10 and is preferably mounted upon a base plate 11, said casing embodying a lower section bolted on said base as at 21. The upper and lower sections of said casing are jointly formed with bearings for a shaft 12 which is usually rotated by a motor also mounted on the base 11. In its upper portion the casing 10 is formed with an inlet opening 13 preferably offset somewhat with respect to the vertical in order to direct the fuel toward the inner surface of the casing and in its lower portion said casing is formed with an outlet 14 through which the

fuel is expelled or projected by the mechanism to be described.

This impelling or projecting mechanism for the coal or other material consists of a series of impellers revoluble in the casing 10 by the shaft 12. If rigid impellers are used it is often found that unduly large pieces of hard material wedge between the inner surface of the casing and the adjacent end portions of the impellers and as a result the mechanism becomes clogged, under which circumstances parts are apt to be broken. On the other hand, if plain pivoted impellers are used unduly large pieces of material will result in the impellers being moved on their pivots so that the material escapes that particular impeller between the outer edge of the impeller and the casing and passes to the next succeeding impeller so that an abnormal load is placed upon the succeeding impeller. For this reason, in the present instance the impellers are preferably formed of a plurality of sections each one of which is movable with respect to the other so that if a large piece of hard substance such as slate, wood or the like should engage the impeller one or more of the impeller sections may move on its pivot to permit the same to escape, while the remaining sections will remain in normal position and retain the fuel being carried thereby, with result that such fuel as is carried by these last mentioned impeller sections will not escape or move past the impeller and thereby impose an abnormal burden upon the next succeeding impeller.

As a matter of manufacturing economy and as a matter of convenience, these sectional impellers indicated at 15 are preferably secured or carried by the shaft by means of a plurality of plates 16 keyed on said shaft. Two of said plates, 16 which may be termed end plates, abut against the walls of the casing while the remainder of these plates are spaced axially of the shaft so that one plate is extended between each two adjacent impeller sections. Mounted in these plates are a plurality of pins 17 extending axially of the shaft, the number of pins corresponding to the number of impellers to be carried by the shaft. Pivotally mounted on said pins 17 are a number of members, which might be termed fingers, constituting the impeller sections 15. Said sections or fingers 15 project from the plates into close proximity to the inner surface of

the casing. With the pivot pins for the impeller sections carried by the shaft in this fashion, said pins are well reinforced against any bending strains which might be placed upon them by the load carried by the impeller sections themselves.

In the structure shown in the present instance the impellers are each composed of fourteen sections each five inches long, one 10 inch wide and one-half inch thick and there is about one-fourth to one-half inch clearance between the tips of said impeller and the casing. The spacer plates are preferably about twelve inches in diameter and 15 one-sixteenth inch thick. With this construction, the coal should be crushed to a size not larger than two and one-half inches.

What I claim is:

1. In a device of the character described, 20 the combination of a casing having inlet and outlet openings for material to be handled by the device, a shaft journaled in said casing, a series of plates mounted on said shaft, a plurality of pivot pins carried by said 25 plates and a sectional impeller pivoted on

each of said pins and projecting into proximity to the surface of said casing.

2. In a device of the character described, the combination of a casing having inlet and outlet openings for material to be handled 30 by the device, a shaft journaled in said casing, a series of plates mounted on said shaft, a plurality of pivot pins carried by said plates, and an impeller pivoted on each of said pivot pins, each impeller comprising a 35 series of fingers arranged axially of said shaft with one of said plates positioned between each pair of adjacent impeller fingers.

3. In a device of the character described, the combination of a casing having an inlet 40 and an outlet for material to be handled, a shaft journaled in said casing, a plurality of pivot pins revolvable with said shaft, a sectional impeller pivoted on each of said pins, and means mounted on said shaft for 45 supporting said pivot pins and reinforcing the same against bending strains imposed thereon by said impeller encountering the material being handled.

CHARLES E. McDONNELL.
